CURB CONSTRUCTION

James W. Reardon, Boston, Mass.

Application September 22, 1939, Serial No. 296,079

9 Claims.

(Cl. 94—31)

This invention relates primarily to highway construction, and especially to curbings or facings for sidewalks bordering a highway proper, although capable of other uses, such as for highway lane dividers, guard rails, safety islands, gasolene filling station curbs, edgings or copings for lawns and flower beds, and the like.

The general object of my invention is to provide a strong and durable curbing construction which is lighter and less expensive than the curbing constructions now in general use, and which can be accurately set with a minimum of labor and skill.

The invention will best be understood from the following description in conjunction with the accompanying drawing. It is to be understood that the invention is not limited to the details of construction and arrangement of parts illustrated in the drawing, since the invention as defined by the claims hereinafter appended, may be otherwise embodied without departure from the spirit and scope thereof.

It is also to be understood that the terms here used are for the purpose of description and not of limitation, and it is not intended to limit the invention claimed herein beyond the requirements of the prior art.

In the drawing:

Fig. 1 is a perspective view showing a construction embodying my invention;

Fig. 2 is a view in cross section of a curbing construction embodying my invention;

Fig. 3 is an exploded perspective view of upper and lower portions of one of the supporting members;

Fig. 4 is a transverse section illustrating certain modifications;

Fig. 5 is a transverse section illustrating certain further modifications.

In Fig. 2 of the drawing, a portion of the paved surface of a sidewalk A adjoins a portion of the paved surface of a highway B. The level of the sidewalk A is raised somewhat above the level of the highway B, and the vertical edge thereof extending above said highway is protected by a curb or facing panel 1 held by bolts 2 to the brace or bracket 3 of a supporting member C which comprises said bracket 3 and an anchor 4 joined by bolts 5 as shown more fully in Fig. 3. The anchor 4 is held firmly in its position at the junction of said highway and sidewalk by the material in which it is embedded, which may be a portion of said highway and said sidewalk, or may be a concrete anchorage formed expressly for the purpose, such as the concrete post 6

here shown. The panel 1 is preferably a metal strip having a bead along its upper edge as shown at 1a. This bead provides great strength and endurance and prevents warping of the panel.

5 It is often desirable to attach reflectors or warning signs to the panel, and in this event, the bulging portion or bead 1a running longitudinally of the strip affords protection for the sign or signal.

10 The supporting member C is shown in greater detail in Fig. 3. The lower or anchor member 4 has a plate 7 having the top surface thereof serrated as shown at 1a and supported by flanges 8, 9 and 10. These flanges, taken together, constitute a flanged post. The exact form and shape of such post is not essential, and the flanged form here shown may be released by any suitable equivalent. It is likewise obvious that the flanges 8, 9 and 10 here shown could be spaced to form

15 three separate posts. In Fig. 3 these flanges 8 and 9 are jointed at an angle of 180° to lie in one plane, while the bracket-like flange 10 is disposed at a right angle thereto. This form, while eminently suitable, is not essential, as these flanges

20 25 may well be disposed at different angles. The flanges 8 and 9 each have an aperture as shown at 11, and the flange 10 has a jagged edge 12. While the exact location of jagged edges and apertures is not controlling, all of said flanges should be provided with some such means, such as apertures, jagged edges, projecting lugs or the like, designed to enable the concrete or other substance in which said anchor flanges are embedded to grip them and hold them against upward displacement. The top plate 7 of the anchor 4 has slots 13 and 14 through which bolts

30 35 40 extend upwardly. The bolt heads 15 which connect pass through said narrow slots are permitted sliding but not rotative movement by their inclusion in the channel structures or shields 16 and 17 each comprised of side walls 18 and 19 and a bottom wall 20 formed integrally with said plate 7. Channels may be formed in the body of the plate 7 if desired, or the shields 16 and 17 may be simplified or modified to suit the convenience, provided the anchorage material is not allowed to interfere with the bolt heads, and other means may be used to keep the bolts from turning. When the anchor 4 is embedded in the

45 50 55 concrete post 6, only the plate 7 extends above the concrete, although channels may be formed in the concrete leading to the open end of the shields 16 and 17 to allow the insertion of bolts after the anchor has been embedded. The channel structures 16 and 17 then prevent the con-

crete from interfering with the bolts 5, allowing them to slide as desired for the proper adjustment of the bracket 3, thereby allowing said bracket to be placed in position after the anchor 4 has been embedded at the edge of the highway, and moved inwardly toward the sidewalk or outwardly toward the highway or even set obliquely as expedient.

The bracket 3 comprises a horizontal plate 21 serrated on the bottom surface thereof to match and cooperate with the serrations of the top surface of the plate 1 of the anchor 4. An integrally formed vertical plate 22 extends upwardly from the forward or outer edge of the plate 21 and is braced by a flange 23. The plate 21 is slotted as shown at 24 and 25 to allow the bolts 5 to pass through the plate 21. Nuts 26 are turned on the bolts 5 to hold the bracket 3 and anchor 4 fixed in relative position when correctly aligned. The slots 24 and 25 in the plate 21 extend laterally at approximately right angles to the slots in the anchor top 1. This permits the bracket 3 to be moved laterally, as well as inwardly and outwardly, thus permitting adjustment of the bracket 3 with respect to the anchor 4 and a combination of these two lines of movement permits the bracket 3 to assume a diagonal or oblique position with respect to the anchor 4. The vertical plate 22 is also slotted as shown at 27 and 28. These slots extend vertically, thus allowing bolts 2 to be raised or lowered accordingly as it is desirable to raise or lower the panel 1.

In the modified structures shown in Figs. 4 and 5, the curb 29 is a slab or panel of rock, wood or concrete instead of metal. Any equivalent material may, of course, be used. When a shallow, bevelled curbing is desired, as where the level of the sidewalk is only a little higher than the level of the highway, then a device similar to that shown in Fig. 4 is used, but where the distance between the levels is greater, or where the curbstone is thin, hardly more than a facing, then a device like that shown in Fig. 5 is preferable. In both instances the curb 29 is held against the vertical wall 30 of a bracket 31 which is adjustably mounted on an anchor 32 in the manner heretofore described. In this case, however, the anchor 32 has an additional top plate 33 which serves as a platform for the curb 29. The plate or platform 33 is supported by a brace flange 34, the anchor then forming a structure similar to a double bracket, having two platforms and four flanges, as shown in Fig. 4. In Fig. 5, the relatively thin curb 29 is held to the vertical wall 30 by a bolt 35.

The curbing of my present invention is made of comparatively inexpensive materials, and is quickly and easily placed in position, since the structure allows considerable adjustment, avoiding the waste of time and effort usually necessary in digging deep trenches, in lining up heavy curbing materials or in trying to determine in minute detail the exact position in which the anchors must be placed. These anchors may readily be set in concrete at a time when the exact line and grade of the finished curbing are difficult to determine. The highway often presents irregular surfaces, and in some cases is unfinished when the curb anchors are set, and it is therefore very difficult to set these anchors accurately, so that the finished curb will be laid evenly and in line with sidewalk and highway. Once the concrete is hardened, it is practically impossible to correct mistakes of alignment without destroying the concrete post and beginning anew. With my in-

vention, however, it is possible to embed the anchors in merely approximate alignment, requiring little time, skill and effort. My construction permits great saving in labor, as highly skilled labor is not required, and great care and effort in setting the anchors is not needed because of the adjustability provided by my construction. The brackets and panels may be properly aligned after the anchors have been placed. The novel structure herein disclosed permits the panels to be raised or lowered with respect to the level of the anchor or the level of the sidewalk and highway, they may be moved inwardly toward the walk or outwardly away from it, and the brackets may be moved longitudinally of the panels if the bolt holes or ends of the panels do not precisely coincide with the position of the anchor.

Attempts have been previously made to use metal curbings but such curbings have never enjoyed commercial success because they were expensive, and could not be adapted to suit practical requirements.

Stone curbings, known and used for a great many years, have never been wholly satisfactory. They are hard to align, there is a great deal of waste, as the stone must extend far below the surface of the highway, and they fail to keep in line. My modified structure, embodying the principles of my invention, permits the use of stone curbing in inexpensive quantities and with adequate protection against shifting. It is estimated that my new curbing construction has effected a saving of 50% to 75% in the cost of labor and material. This use of my adjustable supporting structure comprising a novel form of anchor and bracket, serves to illustrate clearly that the invention herein disclosed and claimed is a radical departure from the teaching of the prior art, and that it does not merely rely on the substitution of metal panels in place of stone.

I claim:

1. A curbing construction for highways and the like having a series of panels and a series of adjustable supporting members therefor each comprising an anchor member and a brace member, one portion of said anchor member forming at least one post, and another portion thereof forming a supporting table for said brace, said table having a serrated top surface adapted to grip the base portion of said brace, a channel groove, and a bolt adapted to slide in said channel groove and to project through said groove to connect said anchor member and said brace member.

2. A curbing construction for highways and the like having a series of panels and a series of adjustable supporting members therefor each comprising an anchor member and a brace member, said anchor member having a top plate serrated on the upper surface thereof and supported by a flanged post adapted to be embedded in a suitable anchorage material, said plate having slots therein to enable bolts to pass through said plate in any of a variety of positions throughout the extent of said slots, bolts adapted to project through said slots to secure said plate to said brace, said bolts having bolt-heads adapted to slide along the under surface of said plate in proximity to said slots, and shields for enabling said bolt heads to move unimpeded by the anchorage material in which said post is embedded.

3. A curbing support for curbing panels, having in combination, an anchor member and a

brace member, said brace member having a wall plate and a base plate serrated on the bottom surface thereof and having slots adapted to receive bolts from said anchor member in any of a variety of positions throughout the extent of said slots.

4. A curbing support for curbing panels, having in combination, an anchor member and a brace member, said brace member having a base plate and a wall plate, said wall plate having vertically disposed slots, and bolts adapted to pass from said panels through said slots in any of a variety of positions along the extent of said slots to secure said panels to said brace member, said base plate having serrations on the bottom surface thereof and slots adapted to receive bolts from said anchor member in any of a variety of positions throughout the extent of said slots.

5. A curbing support comprising separate anchor and brace members, said anchor member having a post adapted to be embedded in anchorage material and having a table adapted to receive said brace member, said table and brace member each having cooperating slots, the slots of said brace member crossing the cooperating slots of said table, bolts adapted to pass through said cooperating slots whereby said brace member may be secured upon said table in desired adjusted position, and means for shielding said bolts to permit free movement thereof when said anchor member is embedded in said anchorage material.

6. A curbing support comprising separate anchor and brace members, said anchor member having a post adapted to be embedded in anchorage material and having a table adapted to receive said brace member, said table having grooves to receive bolts slidably positioned therein, said brace member having cooperating slots crossing said grooves and adapted to receive said bolts.

7. A curbing support having, in combination, an anchor member and a brace member, said anchor member having a post and a table forming a support for said brace surmounting said post, said table having slots therein to enable bolts to pass through said table in any of a variety of positions throughout the extent of said slots,

bolts adapted to project through said slots to secure said table to said brace, and shields for enabling the heads of said bolts to move unimpeded by the anchorage material in which said post is embedded, said brace member having a base portion provided with slots disposed at substantially right angles to the slots in the table portion of said anchor member, said slots being adapted to receive the bolts of said anchor member in any of a variety of positions along the extent thereof to enable said brace member to be positioned in a variety of positions with respect to said anchor member.

15   8. A curbing support having, in combination, an anchor member and a brace member, said anchor member having a post and a table having serrations on the upper surface thereof forming a support for said brace surmounting said post, said table having slots therein to enable bolts to pass through said table in any of a variety of positions throughout the extent of said slots, bolts adapted to project through said slots to secure said table to said brace, and shields for enabling the heads of said bolts to move unimpeded by the anchorage material in which said post is embedded, said brace member having a base portion having serrations on the lower surface thereof adapted to cooperate with the serrations on the upper surface of said table and provided with slots disposed at substantially right angles to the slots in the table portion of said anchor member, said slots being adapted to receive the bolts of said anchor member in any of a variety of positions along the extent thereof to enable said brace member to be positioned in a variety of positions with respect to said anchor member.

member.

9. A curbing construction having a series of anchor members, a series of curb members each having an upright panel portion and a bracket portion adapted to engage an anchor member, a slot in said bracket portion, a slot in each anchor member adapted to extend across the aforesaid slot and cooperate therewith, and a bolt adapted to pass through said slots to secure said bracket members to said anchor members in any of a variety of positions.

JAMES W. REARDON.
